UNITED STATES PATENT OFFICE.

RALPH M. BARNETT, OF LENOIR CITY, TENNESSEE.

GRATE.

1,172,002.

Specification of Letters Patent.

Patented Feb. 15, 1916.

Application filed July 10, 1915. Serial No. 39,091.

To all whom it may concern:

Be it known that I, RALPH M. BARNETT, a citizen of the United States, residing at Lenoir City, in the county of Loudon and 5 State of Tennessee, have invented certain new and useful Improvements in Grates, of which the following is a specification, reference being had to the accompanying drawings.

- 10 This invention relates to certain improvements in grates and has relation more particularly to a device of this general character especially designed and adapted for use in connection with household ranges or 15 the like and it is an object of the invention to provide a device of this character having novel and improved means whereby water may circulate directly under the fire thus eliminating the use of water backs and coils. 20 Furthermore it is an object of my invention to provide a novel and improved fitting through which the water enters and discharges and which permits the grate to turn or rock. 25 The invention consists in the details of construction and in the combination and arrangement of the several parts of my improved grate whereby certain important advantages are attained and the device is rendered simpler, less expensive and otherwise more convenient and advantageous for use, all as will be hereinafter more fully set forth.

The novel features of the invention will 35 be carefully defined in the appended claims.

In order that my invention may be the better understood, I will now proceed to describe the same with reference to the accompanying drawings, wherein—

40 Figure 1 is a view partly in plan and partly in section of the device as herein embodied; and Fig. 2 is a sectional view taken substantially on the line 2—2 of Fig. 1.

As disclosed in the accompanying drawings S denotes a fragment of a range of conventional construction and with which my improved grate G coacts. As herein disclosed the grate G is of such configuration as to properly fit within the fire box of the 45 stove and is provided at one extremity with a trunnion 1 terminating in the angular portion 2 whereby the same may be operatively engaged with a suitable implement for imparting requisite rocking movement 50 to the grate. The opposite extremity of the

grate G is provided with the trunnion 3 of a materially greater diameter than the diameter of the trunnion 1 and said trunnion is provided with the ports 4 in communication with the ports disposed longitudinally thereof and in communication with the opposite extremities of the conduit 5 formed within the grate 1 and disposed around the margins thereof.

The trunnion 3 projects exteriorly of the 65 stove S and is mounted within the sleeve or fitting 6 provided with the diametrically opposed ports 7 and 8 adapted to communicate with the ports 4 hereinbefore referred to and said port 7 being adapted for communication with a suitable source of water supply while the port 8 is adapted for communication with a conventional boiler or other point of delivery.

The trunnion 3 snugly fits within the 75 sleeve or fitting 6 and has its free end portion reduced to afford an annular shoulder 9 adapted to coact with the annular shoulder 10 within the bore of the sleeve or fitting 6 afforded by restricting the intermediate diameter of the bore of said sleeve or fitting and between said shoulders 9 and 10 is adapted to be positioned suitable packing. Insertible within the outer extremity of the 80 sleeve or fitting 6 and coacting with the outer annular shoulder 11 afforded by the restricted portion of the bore of said sleeve or fitting is a conventional gland nut 12 whereby additional packing may be employed in connection with the trunnion 3. 85 90

From the foregoing description, it is thought to be obvious that a grate constructed in accordance with my invention is of an extremely simple and comparatively inexpensive nature and is particularly well 95 adapted for use by reason of the convenience and facility with which it may be assembled, and it will also be obvious that my invention is susceptible of some change and modification without material departure from the 100 principles and spirit thereof and for this reason I do not wish to be understood as limiting myself to the precise arrangement and formation of the several parts herein shown in carrying out my invention in 105 practice.

What I claim is:—

1. A fire grate having a conduit therein extending substantially entirely around the marginal portion thereof, said grate being 110

provided with an extension having ports in communication with the extremities of the conduit.

2. A fire grate having a conduit therein extending substantially entirely around the marginal portion thereof, said grate being provided with an extension having ports in communication with the extremities of the conduit, said extension serving as a trunnion, a sleeve surrounding said extension and provided with ports adapted to communicate with the ports of the extension.

3. A fire grate having a conduit therein extending substantially entirely around the marginal portion thereof, said grate being provided with an extension having ports in communication with the extremities of the conduit, said extension serving as a trunnion, a sleeve surrounding said extension and provided with ports adapted to communicate with the ports of the extension, the outer extremity of the extension being reduced to afford an annular shoulder and the intermediate portion of the bore of the sleeve being restricted to afford an annular shoulder, and packing interposed between said annular shoulders.

4. A fire grate having a conduit therein extending substantially entirely around the marginal portion thereof, said grate being provided with an extension having ports in communication with the extremities of the conduit, said extension serving as a trunnion, a sleeve surrounding said extension and provided with ports adapted to communicate with the ports of the extension, said extension having its outer extremity of reduced diameter to afford an annular shoulder, the intermediate portion of the bore of the sleeve being restricted to afford spaced annular shoulders, packing interposed between the shoulder of the extension and the adjacent shoulder of the sleeve, a gland nut coacting with the outer extremity of the sleeve, and packing interposed between said gland nut and the second annular shoulder of the sleeve.

In testimony whereof I hereunto affix my signature in the presence of two witnesses.

RALPH M. BARNETT.

Witnesses:

I. M. HARTSOOK,
A. A. MONGER.
